US00D737347S

(12) **United States Design Patent**
Anantha et al.

(10) **Patent No.:** **US D737,347 S**
(45) **Date of Patent:** **** Aug. 25, 2015**

(54) **FILAMENT SPOOL HOLDER FOR
THREE-DIMENSIONAL PRINTER**

(71) Applicant: **MakerBot Industries, LLC**, Brooklyn, NY (US)

(72) Inventors: **Vishnu Anantha**, Brooklyn, NY (US); **Jackson Seidenberg**, Brooklyn, NY (US); **Taylor S. Goodman**, New York, NY (US); **Marguerite Siboni**, San Francisco, CA (US); **Amanda I. Couto**, Brooklyn, NY (US); **William B. Buel**, Sunnyvale, CA (US)

(73) Assignee: **MakerBot Industries, LLC**, Brooklyn, NY (US)

(**) Term: **14 Years**

(21) Appl. No.: **29/478,424**

(22) Filed: **Jan. 5, 2014**

(51) **LOC (10) Cl.** **15-09**

(52) **U.S. Cl.**

(57) **CLAIM**

What is claimed is the ornamental design for a filament spool holder for three-dimensional printer, as shown.

DESCRIPTION

FIG. 1 is a front perspective view of a design for a filament spool holder for three-dimensional printer.

FIG. 2 is a rear perspective view of the design.

FIG. 3 is a left side view of the design.

FIG. 4 is a right side view of the design.

FIG. 5 is a front view of the design.

FIG. 6 is a back view of the design.

FIG. 7 is a top view of the design; and,

FIG. 8 is a bottom view of the design.

1 Claim, 6 Drawing Sheets
